METHOD OF AND APPARATUS FOR OPENING PLUGGED PIPE IN A WELL BORE

Lawrence K. Moore, Natchez, Miss.

Application April 10, 1956, Serial No. 577,365

11 Claims. (Cl. 166—44)

This invention relates to apparatus suitable for use on a wire line or cable for cleaning out material clogging the bore of a continuous length of pipe or separated lengths of pipe called a fish, such as drill pipe, drill collars, tubing, jars, bumper subs and the like in a well, and more particularly to a method and apparatus for both cleaning out and carrying away cuttings and debris plugging such pipe or fish in an oil or gas well, or well being drilled for such a purpose.

This application is a continuation-in-part of my co-pending application Serial No. 349,385, entitled "Hydraulic Clean-Out Apparatus for Opening Plugged Well Pipe," filed April 17, 1953, and now abandoned.

The inside of a continuous length of pipe disposed in a well bore may become plugged with heavy or dehydrated mud or lost circulation material, and a fish left in a well may become additionally plugged with wall cuttings and debris which may fall into the top of the fish.

It is desirable to clean out the bore of a continuous length of plugged pipe or fish for any one of a number of reasons. Thus, for example, it may be necessary to clean out the plug to regain circulation. In addition, it may be necessary to remove such a plug in order to run some form of wire line tool, such as a free point indicator, back-off tool, or gun perforator to a point in the pipe or fish below the plug. The running of any of the above-mentioned wire-line devices, after removal of the plug, will usually greatly facilitate recovery of the plugged pipe or fish from the well bore.

Prior to my invention a conventional method for cleaning out a plugged string of drill pipe or tubing, or for cleaning out a fish, included the steps of lowering a continuous string of smaller pipe into the plugged pipe or tubing and washing out the plug by a circulation of fluid downwardly inside the smaller pipe. This method obviously was very time-consuming and expensive for the reason that the smaller pipe must first be secured, transported to the location, and made up in individual joints. While all these preparations were made, the string of pipe to be washed out could, in addition, stick higher in the hole.

Another method consists of running spudding tools on a wire line in an attempt to knock the bridge out of the pipe or fish. This, obviously, is not always effective if the plug extended over any long interval in the pipe, for the reason that there is no means of actually removing the plugging material from the pipe. Still another method consists of the running of small-diameter hydrostatic bailers on a wire line and attempting to bail the material from the pipe. This method has serious limitations in that the bailer can only bring out small amounts of material on each run, thus requiring many runs in the hole. In addition, the washing or loosening effect of the bailer is often not effective in breaking up the material so that it can enter the bailer, and further, bailers of this type often tend to stick, thus further complicating the fishing job. Thus, prior to my invention, if any of

the above-mentioned methods failed to unplug the pipe or fish, the only alternatives were to remove the pipe by making outside mechanical cuts when possible, which is a very expensive method, or abandoning that portion of the plugged pipe remaining in the hole.

It will be readily appreciated by those skilled in the oil well drilling art that my hydraulic clean-out device, that can be run on a wire line or cable and thus wash out as much as 500 feet of plug on one run, would save considerable time and be much more effective and advantageous than any of the conventional methods mentioned above.

The present invention provides a method operable with a wire line or cable for cleaning out the bore of a plugged pipe or fish comprising the operational steps of: lowering means forming a nozzle into and completely below the upper end of the pipe, such as, for example, drill pipe or tubing disposed in a well bore above a plugged fish; and circulating a fluid downwardly inside the drill pipe or tubing and through the nozzle-forming means at a pressure to form a jet of fluid at the lower end of the nozzle-forming means, whereby material plugging the pipe or fish may be eroded or washed out of the bore of the pipe or fish by the force of the jet and carried away by flow of the fluid through perforated holes, circulation ports, or a break in the pipe, and upwardly between the well bore and the unplugged pipe. It will be appreciated that a skirt, overshot or washover pipe may be appended to the unplugged pipe and positioned to surround the plugged pipe whereby fluid will circulate through the nozzle forming means into the fish, through said skirt, overshot or washover pipe and then upwardly in the well bore.

In my method, the nozzle-forming means may be easily lowered into the well by a conventional wire line or cable. It is well known by those skilled in the art as aforementioned that a wire line may be run into a well at an extremely faster rate than a continuous length of small tubing or small drill pipe which must be lowered section by section. Hence, the present invention provides a more efficient and economical method of cleaning out material plugging the bore of a fish.

The word "pipe" as used above, and as used herein-after is meant to include not only the usual string of drill pipe, but also the usual string of production tubing. This pipe is an outer pipe, and in practicing my invention, I usually employ a smaller pipe or tubular member which is usually externally flush and which is hereinafter referred to as tubing for use inside of said outer pipe which I refer to as pipe. It will be appreciated that the outer pipe, i.e. drill pipe or production tubing, may be provided with threads or a threaded sub to engage the fish. It will be appreciated still further that said pipe may be provided with other means of engaging the fish, such as an overshot equipped with slips.

According to a feature of the invention, a section of small-diameter tubing is lowered into a pipe in a well on a wire line or cable to a position substantially below the upper end of said pipe and near its lower end or near a plug in the pipe. The external surface of the tubing is sealed or partially sealed to the internal surface of the pipe at least at one point along the length of the tubing. The tubing is then brought into close relationship with debris plugging the pipe or fish. A fluid is thereafter circulated through the pipe and subsequently through the tubing and into contact with the debris plugging the pipe or fish to erode and remove the same from the pipe or fish. In accordance with this feature of the invention, the tubing is lowered and/or pumped farther into the pipe or fish as the plugging material is eroded or washed out of it so that the jet may be positioned

a most effective distance from the material plugging the pipe or fish.

According to a specific aspect of the invention the tubular member or nozzle to be lowered in a pipe is provided with apertures and means are provided to lower the tubing into the pipe. Collar means are also provided slidably on the tubing and resilient means are fixed to the tubing to urge the collar means upwardly along the tubing to cover the apertures. The sealing means are then fixed to the collar means, whereby the collar means may be forced downwardly against the resilient means to open the apertures to relieve stress on the lowering means any time the fluid pressure in the pipe above the tubing section becomes excessive.

The sealing means for use in pipe may comprise a tubing anchor including a length of tubing or hollow body portion having a first radial projection on its lower end. In this case a tubing is provided with a second radial projection and is disposed concentrically with and contiguous to the body portion of the tubing anchor whereby the radial projection of the tubing section may engage the first radial projection of the body portion to limit the downward movement of the tubing section along the body portion. The tubing section is then slidably mounted on the body portion to be always positioned a most effective distance from the material plugging the pipe or fish.

According to a still more specific feature of the invention, the sealing means includes an annular resilient body having a substantially V-shaped cross-section, the body being fixed to the tubing section itself with the vertex of the V disposed in engagement with the inner surface of the pipe. According to this feature of the invention, stress on the lowering means is relieved by bending the outer edge of the resilient body downwardly to permit the flow of fluid between the resilient body and the pipe in addition to the flow through the tubing section.

The invention also contemplates the use of apparatus for use in pipe comprising a hollow body portion such as tubing, packing means slidable on the tubing to provide a fluid-tight seal between the said pipe and the tubing, check means on the tubing for limiting downward movement of the packing means thereon, and a shoulder on the pipe to limit downward movement of the packing means therein. In case the packing means should come off of the tubing, the shoulder on the pipe insures that the packing means will not fall into the bottom of the well where it might cause damage or where considerable trouble might be encountered in retrieving it.

According to a specific feature of the invention, a wire line or flexible cable is connected to the tubing so it may be easily lowered into and lifted out of the well.

An aspect of the invention involves the use of a circulating head connected between the flexible cable and the tubing to provide communication from the pipe above the packing means through the upper end of the tubing. In addition, an outwardly-extending shoulder may be provided at the upper end of the tubing to prevent it from falling through the packing means in the event that the flexible cable becomes severed accidentally.

In accordance with another feature of the invention, the check means may comprise a member associated with the tubing to shear when sufficient force is applied to the tubing, whereby the tubing may be removed from the pipe if the packing means becomes stuck in the pipe.

It is, therefore, an object of the invention to provide an improved method of cleaning out a plugged pipe or fish in a well bore.

It is a further object of the invention to provide means suitable for use on a wire line or cable for washing out the bore of a plugged pipe or fish.

It is another object of the invention to provide a device for preventing separate component parts of a clean-out tool from falling into a well.

A further object of the invention is to provide means

for preventing apparatus useful for cleaning out a plugged pipe or fish from becoming stuck in pipe in a well.

These and other objects and advantages of the present invention will be better understood when considered with the following description taken in connection with the accompanying drawings made a part of this specification, wherein several embodiments are illustrated by way of example. The device of the present invention is by no means limited to the specific embodiments illustrated in the drawings since they are shown merely for purposes of description.

Fig. 1 is an elevation view of a well derrick and other apparatus generally required for performing the method of the invention;

Fig. 2 is a broken away sectional view of a tubing anchor shown employed with other apparatus of the invention to clean-out material plugging a fish in a well bore;

Figs. 3 and 4 are broken sectional views of alternative embodiments of the invention to be used with the apparatus shown in Fig. 2;

Figs. 5, 6 and 7 are broken away sectional views of three forms of another embodiment of the invention;

Fig. 8 is a sectional view of another clean-out apparatus constructed in accordance with another embodiment of the invention;

Fig. 9 is a sectional view of a portion of the apparatus shown in Fig. 8 in its operative position to clean-out material plugging a fish; and

Fig. 10 is a sectional view of a sub connected between the lower end of a drill pipe and the upper end of a fish to provide circulation ports when it is desirable to screw the unplugged pipe into the fish.

In the drawings in Fig. 1 a derrick 10 is shown provided with a crown block 12 over which a wire line or cable 14 is disposed into a well, not shown. A table 18 is shown above the well which is operated by a mechanism 16 that also lowers and hoists the wire line 14 into and out of the well. A pump assembly 20 is also provided to circulate wash fluid down through the drill pipe and up between the well bore and the drill pipe.

A tubing anchor 22, which may be employed with the method of the invention, as shown in Fig. 2 comprising a body portion or length of tubing 24 having a lower extremity or stinger 26. The stinger 26 is provided with nozzle-forming means at the bottom thereof to erode out material 28 plugging a fish 30. The fish 30 is disposed below a section of drill pipe 32 in a well bore 34. It is to be specially noted that the tubing anchor 22 may be lowered in on the wire line 14 and set in the pipe 32. The tubing 24 is threaded into a head 36 which is, in turn, threaded into a circulating head 38 having apertures 40 to permit wash fluid pumped down the pipe 32 to enter the tubing 24 at its upper end. The wash fluid is then forced out of the lower end of the stinger 26 to clean out the fish 30.

The tubing anchor 22, as shown in Fig. 2, is not fixed in the pipe 32. However, this may be accomplished easily in a well known and conventional manner. The tubing anchor 22, in addition to the head 36, comprises a sealing packer 42 disposed on the outside and at the lower end of the head 36, an expander sleeve 44 disposed on the outside of the tubing 24 and having fingers 46 extending up into the space between the packer 42 and the head 36. A slip assembly 48 there shown includes a cylinder portion 50 surrounding the tube 24 for supporting three sets of slips 52 by means of suitable spring extensions 54. Drag springs 56 are also provided on the cylinder 50 to set the tubing anchor in the pipe 32. A screw 58 is disposed in the cylinder 50 to guide the cylinder 50 up and down along the tubing 24, the screw 58 riding in a slot arrangement 60. The slot arrangement 60 provides means to produce relative rotation for the slip assembly 48, whereby the expander sleeve 44 may be driven into the space between the slips 52

and urged upwardly to lodge the packer 42 between the head 36 and the pipe 32. The tubing anchor 22 is lowered into the pipe 32 with the screw 58 riding in a slot 62. The tubing anchor 22 is removed from the pipe 32 by lifting the anchor means of the wire line 14 with the screw 58 lodged at a point 64 or at a point 66 in the slot arrangement 60.

After the tubing anchor is lowered to an appropriate depth within the pipe 32 with the screw 58 at the top of the slot 62, the wire line is lifted to send the screw 58 down to the point 64. The wire line 14 is then slackened and the screw 58 is permitted to ride up into the slot 68 so that the expander sleeve 44 will be driven into the space between the slips 52. The slips will bite into the pipe 32 and the packer 42 will be set between the head 36 and the pipe 32. To remove the tubing anchor 22 from the well an upward force is applied to the wire line 14 which moves the tubing 24 upwardly to place the screw 58 at the point 66. This takes the wedge of the expander sleeve 44 out of the slips 52, causes the slip to disengage the pipe 32 and pressure on the packer 42 against the pipe 32 is relieved by relative downward vertical movement of the fingers 46 along the tubing 24.

After the tubing anchor 22 is set in the pipe 32, according to the method of the invention, wash fluid is circulated down through the pipe 32, through the apertures 40 of the circulating head 38, through the tubing 24 and out the lower end of the stinger 26 to erode the material 28 out of the fish 30 and to carry it away up the well in the space between the pipe 32 and the well bore 34.

In the operation of the clean-out apparatus shown in Fig. 2 it often happens that material 28 adjacent the internal surface of the fish 30 becomes washed out before the material at the center of the fish is loosened. This often causes the material 28 in a solid form to be forced down to a greater depth into the fish 30. For this reason it is desirable to move the stinger 26 farther into the fish 30 to place it a most effective distance from the material 28 to continue the washing method. It is generally undesirable and too troublesome to move the tubing anchor 22 step by step down the unplugged pipe so that the stinger 26 will be placed step by step farther into the fish 30. Alternative stinger assemblies are shown in Figs. 3 and 4 which may be employed to solve this problem.

A stinger assembly 70 is shown in Fig. 3 comprising the tubing 24 with a radially and outwardly extending flange 72 at its lower end. A nozzle assembly 74 is then provided outside of the tubing 24 with a flange 76 extending radially inwardly to the external surface of the tubing 24. The flanges 72 and 76 thus cooperate to limit the downward vertical movement of the nozzle assembly 74. Material 28 plugging the fish 30 is also shown in Fig. 3, the portion of the material adjacent the internal surface of the fish 30 being washed away. In the operation of the stinger assembly 70 wash fluid is forced down through the tubing 24 and out the lower end of the nozzle assembly 74. Force of the fluid against the upper surface of the material 28 prevents the nozzle assembly 74 from directly engaging that surface. Material 28 is thus eroded away by flow of the wash fluid through the lower end of the nozzle assembly 24 and carried away up the fish 30 between the nozzle assembly 74 and the fish 30 to the top of the fish where it is further carried away up the well between the well bore 34 and the pipe 32 as indicated by the arrows 78 in Fig. 3 and the arrows 80 in Fig. 2.

A similar stinger assembly 82 is shown in Fig. 4 wherein the tubing 24 is provided with an inwardly extending flange 84. A nozzle assembly 86, slidably within the tubing 24 is also provided including an outwardly and radially extending flange 88 to engage the flange 84 and limit the downward vertical movement of the nozzle

assembly 86. The material 28 is shown in the same manner in the fish 30 in Fig. 4 and is eroded away and carried away in the same manner as described with respect to the stinger assembly 70 shown in Fig. 3.

In Fig. 5 an alternative embodiment of the invention is shown. As illustrated in Figs. 2, 3 and 4, a packer 42 may be fixed to the pipe 32 and a nozzle assembly or apparatus is also employed wherein a packer is fixed to a movable nozzle assembly. Such a device is shown in Fig. 5 comprising a length of tubing or spout-forming means 90 having a circulating head 92 for a top portion and a stinger 94 forming its bottom portion. The nozzle-forming means 90 is a length of tubing which may be conveniently lowered into the pipe 32 by means of the wire line 14. The tubing 90 may be most conveniently lowered into the well by pumping wash fluid down into the pipe 32, the flow between the tubing 90 and the pipe 32 being restricted by a cylindrical body 96 fixed to the tubing 90 at a point along its length. The body 96 may be made of a rigid metallic material, or alternatively, of a resilient material. Its function is merely to divert most of the fluid in the pipe 32 thru it and preferably to prevent most of the fluid from flowing around it. After the tubing 90 is lowered into the pipe 32 with the stinger 94 projecting into the fish 30 to clean out the material 28, wash fluid may be circulated down the pipe 32 through apertures 98 in the head 92 through the tubing 90 and the stinger 94 to erode the material 28 out of the fish 30.

It is common to lower tools into pipes such as the pipe 32 on a wire line by two methods. Tools may be lowered into pipe and carried down simply by virtue of their own weight or they may be pumped down. In the latter case, clearance between the tool and the pipe is restricted. If, for example, the tubing anchor 22 is pumped down, means may also be provided to close the upper end of the tubing 24. However, when wash fluid is introduced and forced into the pipe 32 the force on the tubing anchor 22 may be so great that the wire line 14 may be severed and the whole tubing anchor 22 may fall into the well and cause considerable damage. In addition, considerable amount of time, trouble and expense may be required to recover the tool.

In order to prevent the tubing 90 from being pumped off the wire line 14, preferably the body 96 may have the shape as shown as a body 96' in Fig. 6. In this embodiment of the invention, the body 96' has an annular shape with a V-shaped cross-section, the vertex of the V being in contact with the internal surface of the pipe 32. Excessive pressure above the body 96' may thus be relieved by bending movement of the outer edge of the body 96' as indicated by the arrows 99 in Fig. 6. Fluid pumped into the pipe 32 above the body 96' may then be permitted to flow not only through the apertures 98 and the tubing 90 but also between the body 96' and the pipe 32. Such a device may, of course, be employed with the tubing anchor 22 as shown in Fig. 2. However, when employed with the tubing 90 as shown in Figs. 5 and 6, the body 96' serves a dual purpose. That is, it provides a seal fixed to the tubing 90 but slidable with respect to the pipe 32 to permit the tubing 90 to be pumped down the pipe 32 and to restrain flow of fluid between the tubing 90 and the pipe 32 when material 28 is being eroded out of the fish 30. However, if excessive pressure exists above the body 96', the body also relieves against excessive pressure created above it. Thus, it may prevent the tubing 90 from being pumped off the wire line 14.

A similar safety device is shown in Fig. 7 wherein the tubing 90 is disposed in a length of pipe 32. The tubing 90 in this case is preferably provided with a shoulder 102 to support a spring 104 coiled around the exterior of the tubing 90 at a position just above the shoulder 102.

Atop the spring 104 a cylinder 106 is situated having apertures 108 conforming to a plurality of apertures 110 in the tubing 90. The body 96' is then fixed to the exterior and at the upper end of the cylinder 106 to perform the same function as illustrated in Fig. 6. The body 96 in Fig. 5 may of course be substituted for the body 96' as shown in Fig. 7.

The body 96' in Fig. 7 provides the same functions, i.e. to seal the tubing 90 to the pipe 32 and to provide a safety valve for fluid flow between the pipe 32 and the body 96'. In addition, should the pressure above the body 96' become extremely excessive, force on the body 96' will drive the cylinder 106 down the tubing 90 to compress the spring 104. The spring 104 may be compressed to such an extent that the apertures 108 in the cylinder 106 coincide with the apertures 110 in the tubing 90. In this case fluid flow is not only permitted between the body 96' and the pipe 32 but also completely through the tubing 90 to its lower extremity and out the apertures 110 and down the pipe 32 between the tubing 90 and the pipe 32. In this manner a double safety feature is provided to prevent excessive pressure above the body 96' from severing the tubing 90 from the wire line 14. As stated previously, the body 96' need not necessarily be used with the cylinder 106, the body 96 also being adapted for that use. In this case the only relief given is by the movement of the cylinder 106 to place the apertures 108 over the apertures 110 to provide communication from inside the tubing 90 to the space outside the tubing 90 between the pipe 32 and the tubing 90 below the body 96'.

An alternative embodiment of the invention is shown in Fig. 8 comprising a circulating head 112 connected from the wire line 14 to a length of tubing 114. A gland 116 is then slidably mounted on the tubing 114 with its downward relative vertical movement limited by a pair of check means or shear pins 118. The gland 116 is provided with a packing nut 120 to loosen or tighten the packing therein as the case may require. The lower end of the circulating head 112 is provided with a shoulder 122 to rest on the packing nut 120 to prevent the tubing 114 from being lost in the well in the event that the wire line 14 becomes accidentally severed. The packing nut 120, which is connected to the gland 116, is limited in movement down the pipe 32 by a shoulder 124 thereon having a seat 126 at the bottom thereof to engage the lower end of the gland 116. The gland 116 may be provided with a resilient O-ring 128 as shown.

It is apparent that the shoulder 124 serves a dual function. It provides means to fix the position of gland 116 in pipe 32 and also prevents the gland from falling deep into the well if it should accidentally come loose from the tubing 114.

The shear pins 118 also serve a dual purpose. In the first place they simply limit the downward movement of the gland 116 on the tubing 114. In addition, if the gland 116 should happen to become stuck within the shoulder 124, an upwardly directed force may be applied to the wire line 14 to pull the tubing 114 through the gland 116 and out of the well. The inside diameter of the gland 116 is such that a string shot for unscrewing the pipe may be lowered into the fish 30 after the material 28 has been cleaned out as shown in Fig. 9. The tubing 114 and the gland 116 are shown in Fig. 9 in their operative positions to clean the material 28 out of the fish 30. An overshot 200 with slips 201 are provided at the lower end of pipe 32 to engage fish 30.

As shown in Fig. 9 a packing material 130 is forced into the space between a cylinder 132 forming the gland body and the packing nut 120. If the material 28 should happen to slide down the inside of the fish 30, it will be desirable to lower the tubing 114 farther into the fish. For this reason, the tubing 114 is made slideable through the gland 116. In order to overcome excessive friction in the gland 116, however, a valve (not shown) operable

to slackening of the wire line 14 may be provided within the circulating head 112 to close the upper end of the tubing 114 and thereby permit the tubing 114 to be pumped through the gland 116.

It may be desirable to screw into plugged pipe with unplugged pipe. However, in this case it is necessary to provide communication from a point inside the plugged pipe above the plugging material to a point outside the unplugged pipe. For this reason, a sub 134, shown in Fig. 10, with apertures 136 may be threaded onto the lower end of the unplugged pipe 32 and into plugged pipe 202, the apertures 136 in the sub 134 providing outlets for wash fluid emanating from the lower end of the stinger 138 eroding the material 28 out of the pipe 202. The material is then carried away through the apertures 136 up the well bore between well bore 34 and the pipe 32. It will be appreciated that the sub 134 should be provided with a seat such as the seat 126 if the tool of Fig. 8 is employed therewith.

It is to be understood that the term "nozzle-forming means" as referred to herein is not to be limited in definition to means forming a frusto-conical internal surface converging toward an orifice, but that it means a tube like member to produce a jet of fluid having a cross-sectional area substantially smaller than the unplugged pipe into which the "nozzle-forming means" is lowered. In this definition, a jet of fluid is intended to mean that preferably most of the fluid flowing in the pipe also flows inside the nozzle-forming means and not around it between it and the pipe.

It is thus apparent that the method of the invention may be employed with the use of conventional or novel nozzle-forming means to clean plugging material from a continuous length of pipe, e.g. see Fig. 10, or from a fish disposed in a well bore below pipe such as drill pipe. The method requires the use of only a wire line and thus may be performed quickly and inexpensively. The embodiment of the invention shown in Fig. 5 also illustrates how simple a form the novel apparatus of the invention may take. The alternative embodiments illustrated in Figs. 6, 7, 8 and 9 also show how a number of novel structures may also be employed in addition with the clean-out apparatus to prevent such clean-out apparatus from falling into a well, e.g. by being pumped off of a wire line. The embodiment shown in Figs. 8 and 9, in addition, is provided with the shear pins 118 to permit subsequent recovery operations even though the gland 116 should become stuck in the pipe 32. The apertures 136 of sub 134 in Fig. 10, of course, need not be machined therein, but may be provided by shooting a gun perforator. It is, of course, obvious that many other changes and modifications of the invention may also be made without departing from the true scope as defined in the appended claims.

What is claimed is:

1. Hydraulic apparatus for opening a plugged fish to be removed from a well hole comprising a pipe adapted to be extended into said hole, to a location adjacent the fish to be removed; a fishing tool attached to the lower end of said pipe, said tool including a cylindrical body of the same diameter as the pipe and a skirt depending from the lower end of said body and formed to an inner and outer diameter greater than the inner and outer diameters, respectively, of the body, said skirt being adapted to receive the upper end of the fish to be removed; an elongated tubing extending longitudinally and centrally of said pipe, said tubing having its outer surface spaced inwardly a substantial extent from the inner surface of the pipe and body of the fishing tool, said tubing being formed open at its lower end for exerting fluid pressure therethrough against debris accumulating within said fish, the tubing being shiftable in the direction of its length within the pipe and fishing tool body and when so shifted extending a distance sufficient to bring the lower end of the tubing to a level lower than the fish-

receiving end of the skirt; and means providing a seal interposed between the outer surface of the tubing and the inner surface of said pipe, to prevent a backward flow of fluid pressure within the pipe exteriorly of the tubing, beyond the location of the seal.

2. Hydraulic apparatus for opening a plugged fish to be removed from a well hole comprising a pipe adapted to be extended into said hole, to a location adjacent the fish to be removed; a fishing tool adapted to be attached to the lower end of said pipe, said tool including a cylindrical body of the same diameter as the pipe and a skirt depending from the lower end of said body and formed to an inner and outer diameter greater than the inner and outer diameters, respectively, of the body, said skirt being adapted to receive the upper end of the fish to be removed; an elongated tubing extending longitudinally and centrally of said pipe, said tubing having its outer surface spaced inwardly a substantial extent from the inner surface of the pipe and body of the fishing tool, said tubing being formed open at its lower end for exerting fluid pressure therethrough against debris accumulating within said fish, the tubing being shiftable in the direction of its length within the pipe and fishing tool body and when so shifted extending a distance sufficient to bring the lower end of the tubing to a level lower than the fish-receiving end of the skirt; and means providing a seal interposed between the outer surface of the tubing and the inner surface of said pipe, to prevent a backward flow of fluid pressure within the pipe exteriorly of the tubing, beyond the location of the seal, said means comprising an internal, annular shoulder formed upon the inner surface of the pipe, and a packing gland having an axial bore in which said tubing is slid able, said gland being bodily slid able upon the tube and being proportioned to engage against said shoulder, the gland having packing means forming a part at least of the wall of said axial bore and engaging said tubing to prevent leakage between the tubing and gland.

3. Hydraulic apparatus for opening a plugged fish to be removed from a well hole comprising a pipe adapted to be extended into said hole, to a location adjacent the fish to be removed; a fishing tool adapted to be attached to the lower end of said pipe, said tool including a cylindrical body of the same diameter as the pipe and a skirt depending from the lower end of said body and formed to an inner and outer diameter greater than the inner and outer diameters, respectively, of the body, said skirt being adapted to receive the upper end of the fish to be removed; an elongated tubing extending longitudinally and centrally of said pipe, said tubing having its outer surface spaced inwardly a substantial extent from the inner surface of the pipe and body of the fishing tool, said tubing being formed open at its lower end for exerting fluid pressure therethrough against debris accumulating within said fish, the tubing being shiftable in the direction of its length within the pipe and fishing tool body and when so shifted extending a distance sufficient to bring the lower end of the tubing to a level lower than the fish-receiving end of the skirt; and means providing a seal interposed between the outer surface of the tubing and the inner surface of said pipe, to prevent a backward flow of fluid pressure within the pipe exteriorly of the tubing, beyond the location of the seal, said fishing tool including circumferentially spaced slips affixed to the inner surface of said skirt inwardly from the fish-receiving end of the skirt, said slips projecting radially and inwardly of the skirt and being adapted to engage against the outer surface of the fish to be removed, the slips providing means for gripping the fish when the same is to be lifted from the well hole, said slips being adapted by reason of their projecting radially and inwardly of the skirt to serve as spacer devices for holding the fish centered relative to the skirt in spaced relation to the inner surface of the skirt, thereby to define an annular space between the fish and skirt through which fluid forced through the tub-

ing, and debris forced out of the fish by said fluid, may pass to a location exteriorly of the drill pipe for flow out of the well hole.

4. Hydraulic apparatus for opening a plugged pipe comprising an unplugged pipe adapted to be extended into a well hole to a location adjacent the plugged pipe; means on said unplugged pipe adapted to engage said plugged pipe; an elongated tubing extending longitudinally and centrally of said unplugged pipe, said tubing having its outer surface spaced inwardly a substantial extent from the inner surface of the unplugged pipe, said tubing being formed open at its lower end for exerting fluid pressure therethrough against debris accumulating within said plugged pipe, the tubing being shiftable in the direction of its length within the unplugged pipe and when so shifted extending a distance sufficient to bring the lower end of the tubing to a level lower than the lower end of said unplugged pipe; and means providing a seal interposed between the outer surface of the tubing and the inner surface of said unplugged pipe, to prevent a backward flow of fluid pressure within the unplugged pipe exteriorly of the tubing, beyond the location of the seal, said means comprising an internal, annular shoulder formed upon the inner surface of the unplugged pipe, and a packing gland having an axial bore in which said tubing is slid able, said gland being bodily slid able upon the tube and being proportioned to engage against said shoulder, the gland having packing means forming a part at least of the wall of said axial bore and engaging said tubing to prevent leakage between the tubing and gland.

5. In a well bore having a length of unplugged pipe disposed therein and having a length of up-ended debris plugged pipe disposed in the well below the unplugged length of pipe, the method of circulating fluid to erode and carry said debris from said plugged pipe to the surface through a space exterior of said unplugged pipe, said method comprising the steps of: providing an opening above the debris to the well bore for exit fluid passage; lowering a length of tubing of smaller external diameter than said pipes by means of a wire line into the unplugged pipe and into a position in said pipe so that a portion of said tubing extends from the unplugged pipe into a position in said plugged pipe adjacent the debris; directing a circulating fluid downwardly into said unplugged pipe and into and through said tubing, increasing the velocity of fluid flow in said tubing by positioning means between said tubing and unplugged pipe for diverting fluid in the unplugged pipe into the said tubing; eroding debris out of said plugged pipe by means of the resulting high velocity fluid; circulating said eroded debris and fluid out of said plugged pipe into a space between said plugged pipe and said tubing; further circulating said debris and fluid upwardly and through the said opening provided for fluid exit passage and to the surface of the well bore through the annulus space formed by said unplugged pipe and said well bore; and successively lowering said tubing into the debris plugged pipe so as to maintain the lower portion thereof adjacent to the upper surface of the remaining debris in the plugged pipe and thereby eroding and removing remaining debris from the said plugged pipe.

6. A hydraulic apparatus for opening a debris plugged pipe in a well bore comprising an unplugged pipe adapted to be extended into a well bore to a location adjacent to the plugged pipe; a circulating sub having apertures for fluid passage in the wall thereof connected to said unplugged pipe, said sub having means adapted to engage said plugged pipe; an elongated tubing of smaller diameter than said pipes and movable by means of a wire line in said pipes and extending longitudinally within said unplugged pipe; said tubing being shiftable in the direction of its length within the unplugged pipe and when so shifted extending a distance sufficient to bring the lower end of the said tubing to a level lower than the lower end of said unplugged pipe and into successively lower positions in the plugged pipe to erode debris therefrom; and

means positioned between said unplugged pipe and said tubing for diverting fluid from within said unplugged pipe under pressure into an upper region of said tubing and out of the lower region thereof at increased velocity.

7. In a well bore having a plugged pipe disposed therein, hydraulic apparatus for cleaning out material plugging the pipe, the said apparatus comprising: unplugged pipe means disposed in the well above said plugged pipe; spout-forming means adapted to be raised and lowered on a wire line in said unplugged pipe means so that a portion of said spout means may be extended from said unplugged pipe means into successive portions of the said plugged pipe; and a fluid-restricting device comprising an annular resilient body having a substantially V-shaped cross-section, said body being fixed to said spout-forming means with the vertex of the V disposed in engagement with the inner surface of said unplugged pipe means adapted to divert circulating fluid from the unplugged pipe means into said spout-forming means to cause said circulating fluid to flow through said spout-forming means at increased velocity, the upper end of said spout-forming means at all times adapted to extend above said restricting device while its lower end is positioned substantially below the lower end of said unplugged pipe means and into successively lower portions of the plugged pipe, whereby fluid may be circulated downwardly through said unplugged pipe means and through said spout-forming means at increased velocity to form a stream that will erode debris out of successively lower portions of the plugged pipe and carry said debris to the surface of the well bore through an annulus between the unplugged pipe and the well bore.

8. In a well bore having a plugged pipe disposed therein, hydraulic apparatus for cleaning out material plugging the pipe, the said apparatus comprising: unplugged pipe means disposed in the well above said plugged pipe; spout-forming means including a body portion having a first radial projection on its lower end and another length of tubing extending to the lower end thereof and disposed concentrically with and contiguous to said body portion, said other length of tubing being slidable with respect to said body portion and having an opposite and second radial projection thereon to engage said first radial portion to limit the downward movement of said other length of tubing along said body portion; said spout-forming means adapted to be raised and lowered on a wire line in said unplugged pipe means so that a portion of said spout means may be extended from said unplugged pipe means into successive portions of the said plugged pipe; and a fluid-restricting device comprising a tubing anchor adapted to divert circulating fluid from the unplugged pipe means into said spout-forming means to cause said circulating fluid to flow through said spout-forming means at increased velocity, the upper end of said spout-forming means at all times adapted to extend above said restricting device while its lower end is positioned substantially below the lower end of said unplugged pipe means and into successively lower portions of the plugged pipe, whereby fluid may be circulated downwardly through said unplugged pipe means and through said spout-forming means at increased velocity to form a stream that will erode debris out of successively lower portions of the plugged pipe and carry said debris to the surface of the well bore through an annulus between the unplugged pipe and the well bore.

9. In a well bore having a plugged pipe disposed therein, hydraulic apparatus for cleaning out material plugging the pipe, the said apparatus comprising: unplugged pipe means disposed in the well above said plugged pipe; spout-forming means adapted to be raised and lowered on a wire line in said unplugged pipe means so that a portion of said spout means may be extended from said unplugged pipe means into successive portions of the said plugged pipe, said spout-forming means being provided with apertures; a fluid-restricting device adapted to divert circulat-

ing fluid from the unplugged pipe means into said spout-forming means to cause said circulating fluid to flow through said spout-forming means at increased velocity, the upper end of said spout-forming means at all times adapted to extend above said restricting device while its lower end is positioned substantially below the lower end of said unplugged pipe means and into successively lower portions of the plugged pipe, whereby fluid may be circulated downwardly through said unplugged pipe means and through said spout-forming means at increased velocity to form a stream that will erode debris out of successively lower portions of the plugged pipe and carry said debris to the surface of the well bore through an annulus between the unplugged pipe and the well bore; collar means slidable on said spout-forming means; and resilient means to urge said collar means upwardly along said spout-forming means to cover said apertures, said fluid restricting device being fixed to said collar means, whereby said collar means may be forced downwardly against said resilient means to open said apertures to relieve stress on said lowering means when the fluid pressure on said fluid-restricting device becomes excessive.

10. An apparatus for eroding and removing debris from a length of an up-ended debris plugged first pipe in a well bore by means of a circulating fluid which erodes and carries the said debris from the said first pipe to the surface through a space exterior of the said apparatus, comprising: a second pipe of smaller diameter than the well bore and extending downwardly from an upper portion of the well bore adjacent to the upper end of said first pipe, a circulating sub attached to said second pipe and forming a fluid opening between said first and second pipes, a length of third pipe attached to a wire line extending from above the well bore and being movable by means of said line, said third pipe being of smaller diameter than said first and second pipes and positioned in said second pipe for longitudinal movement therein, so that a substantial portion of the length of said third pipe may be extended from the second pipe into successively lower positions in said first pipe, and means for diverting circulating fluid from said second pipe under pressure into an upper region of said third pipe and out of a lower region thereof at increased velocity into said first pipe, whereby fluid may be circulated downward through said second pipe and through said third pipe at increased velocity into successively lower positions in said first pipe to erode debris therefrom and carry said debris from said first pipe up to the surface through a passage formed between said small diameter third pipe and said first pipe and then through an opening between said first and second pipes and thence to the surface of the bore hole through an annulus between the second pipe and the well bore.

11. Hydraulic apparatus for opening a debris plugged pipe comprising an unplugged pipe adapted to be extended into a well hole, to a location adjacent to the plugged pipe; means on said unplugged pipe adapted to engage said plugged pipe; an elongated tubing extending longitudinally and centrally of said unplugged pipe, said tubing having its outer surface spaced inwardly a substantial extent from the inner surface of the unplugged pipe, said tubing being formed open at its lower end for exerting fluid flow therethrough against debris accumulating within said plugged pipe, the tubing being shiftable in the direction of its length within the unplugged pipe by means of a wire line and when so shifted extending a distance sufficient to bring the lower end of the tubing to a level lower than the lower end of said unplugged pipe and into successive lower positions in said plugged pipe; and means providing a seal interposed between the outer surface of the tubing and the inner surface of said unplugged pipe, to divert circulating fluid flowing downwardly in said unplugged pipe into said tubing and thereby increasing the velocity of flow of said circulating fluid to provide a high velocity stream of said fluid suitable for eroding debris out of a length of the unplugged pipe and carrying said debris to the surface of the

well bore through an annulus between the unplugged pipe and the well bore.
